STRIP FEEDING AND SEVERING DEVICE

Arthur A. Johnson, Bridgeport, Conn., assignor
to Autographic Register Company, Hoboken,
N. J., a corporation of New Jersey

Application August 7, 1941, Serial No. 405,846

18 Claims. (Cl. 164—84.5)

The invention relates to improvements in feeding devices for manifolding stationery, and also to improved manifolding stationery for use with such devices.

More particularly, the present invention provides a positive feed device for manifolding stationery having pins adapted to cooperate with marginal perforations in superposed manifold strips for feeding the strips while maintaining said strips in alignment with each other, and with the writing line of a writing device, and further, means for automatically severing a binding and feeding margin of the strips from the body portions thereof concurrently with and incident to the feeding operation.

The present invention also provides continuous form manifolding stationery having improved registering and aligning apertures therein for cooperation with pin feeding devices, and also adapted to cooperate with the aforesaid margin severing device of the invention.

Manifolding stationery, especially for use in typewriters, generally comprises a plurality of superposed continuous strips (usually printed) interleaved with transfer strips, and divided into successive form lengths by transverse weakened severing lines at form-length intervals.

For positive feeding of the record strips, a series of perforations are usually provided adjacent one or both margins for engagement with pin feed devices provided on the writing device, for instance, on the platen of a typewriter.

Depending upon the number and nature of the strips, it is sometimes possible to maintain adequate alignment of the strips by means of a single row of perforations, adjacent one margin, which engage a corresponding pin feed device on the platen of the typewriter. However, for many types of stationery, the control and support thus provided is insufficient to maintain the desired alignment of the strips on the platen.

The use of a set of apertures in both lateral margins of the stationery, engaging corresponding dual pin feed devices, is generally more reliable, but requires the use of a platen having a pair of feed pin members which are spaced apart by a predetermined distance. If stationery of various widths is to be used, the platen must be replaced, or the spacing of the pin feed members must be altered to accord with the width of the stationery.

It is an object of the present invention to provide continuous multiple strip manifolding stationery having a series of pin feed apertures for cooperation with pin feed devices which reliably

5 maintain the strips in accurate registry with the writing line of a writing device, but so arranged that stationery of different widths requires no alteration in the feeding mechanism, and one margin may be made available for inscription.

To accomplish this, the present invention provides the manifolding stationery with at least two transversely spaced series of feeding apertures adjacent a longitudinal margin of the strips 10 preferably at the left-hand side, and provides a pin feed device with the parallel series of pins to engage said apertures. By thus engaging the spaced rows of pins, even though they be at the same side of the platen, the pile of strips being 15 fed is securely held against skewing relative to the platen.

It has been found that stationery which would fail to maintain its alignment if only one set of feeding pins and apertures were used, is satisfactorily aligned by a double set of parallel feed pins and apertures adjacent one of its margins. Since both sets of pins are at the same end of the platen and the use of pins at the other end of the platen is dispensed with, stationery of any 25 width within the limits of the machine may be used without the necessity of altering the machine.

In order to retain the superposed forms and transfer sheets of continuous manifolding stationery against relative mutual shifting during advancement by a feeding device to an inscription position or writing line, the strips and transfer sheets may be fastened together, for instance 30 by staples or adhesive binding along a margin of the strip, and/or by staples at intervals in the body of the strip. To permit separation of the multiple copies after inscription, the bound or stapled margin is removed by hand from the inscribed portion of the strips.

40 When the superposed manifolding strips, provided with multiple sets of pin feed apertures according to this invention, are bound together at the margin, one set of feed holes is preferably formed in the bound margin and the other set in the body of the strips.

Various means have been proposed heretofore to sever the bound margins of the inscription-receiving portion of manifolding strips. For instance, it has been proposed to use rotary knives 50 or pressure devices which sever or rupture the strip margin incident to the feeding operation.

It is a further object of the present invention to provide a pin feed device which not only performs the function of positively feeding the strips and maintaining their alignment, but also

of severing the bound margin of the strips, incident to its operation.

This is accomplished by so arranging the pin feed device that as the two series of pins rotate with the platen and progressively engage the series of apertures in the severable bound margin and body of the manifolding stationery, the pins of one set move outward along the platen, diverging from the other set of pins, and apply sufficient lateral tension to the bound margin of the strip to sever it along the weakened severing line from the main portion of the strips.

After the pins have rotated beyond the writing line, the inscribed forms and the severed margin are stripped from the pins for delivery in the usual manner. The divergently movable severing pins then move back automatically to their initial position where they are adapted to reengage the incoming strips on the receiving side of the platen.

During the severing operation, the strips are subjected to tension solely in transverse direction, whereby the application of any force tending to disalign the body of the stationery at the writing line is avoided. As there are no blades to become dull, the device requires substantially no maintenance.

In the broader aspects of this feature of the invention, the set of pins may be located at opposite ends of the platen. But when the series of divergent pins and the series of fixed pins are disposed at the same end of a platen, advantage may be taken of the other feature of this invention, and no adjustment will be necessary to accommodate strips of various widths accommodated by the length of the platen.

After a form length of stationery issues from the machine and is severed from the strips, its bound margin having been removed in the aforesaid manner, one or more copies thereof may be reinserted in the machine for typing additional data thereon, reengaging the holes with the traveling series of transversely fixed pins, whereby accurate reregistration and realignment of the form with the writing line of the machine is insured.

Other features and advantages of the invention will appear from the following description, referring to the accompanying drawings, in which:

Figure 1 is a plan view of a portion of a strip of manifolding stationery according to the present invention.

Fig. 2 is a view in side elevation of the combined feeding and strip severing device of the present invention mounted on the end of a rotary platen, and including a portion of a manifolding strip engaged therewith.

Fig. 3 is an axial cross-sectional view of the platen and the feeding and severing device of Fig. 2, substantially along the line 3-3 in Fig. 4.

Fig. 4 is a transverse cross-section substantially along the line 4-4 of Fig. 3.

Fig. 5 is an end view of the platen, and the feeding and severing device shown in Fig. 2.

Fig. 6 is an end view of the fixed pin ring of the feeding and severing device of Fig. 2.

Fig. 7 is a side elevational view of the pin ring shown in Fig. 6.

Fig. 8 is a detail in perspective of a movable feeding and severing pin.

Fig. 9 is a plan view of a portion of a strip of conventional manifolding stationery which may be fed and severed according to the present invention.

Fig. 10 is a perspective view of the device of the present invention applied for feeding and severing the manifolding stationery of Fig. 9.

As illustrated in Fig. 1 of the drawings, the stationery, according to the present invention, comprises a plurality of superposed continuous record strips 20 containing printed matter and lines on each form length. Continuous transfer strips 22 are interleaved with the superposed record strips so that the inscriptions on the topmost strip will be reproduced on each of the underlying strips.

Preferably, the strips 20 are divided into form lengths by transverse weakening lines 24 to facilitate separation of the form lengths after inscription.

According to the present invention, a marginal series of apertures 30 adapted to cooperate with the pin feed device is provided adjacent a lateral margin, preferably the left-hand margin 28 of the stationery, and a similar series of apertures 31 is provided adjacent the same margin, but spaced inwardly on the strip from the apertures 30. Apertures 30 and 31 are preferably arranged in parallel rows, with the apertures in the two rows in mutual transverse alignment. When the stationery is used with a pair of pin fed devices of which only one or two pins are fully engaged with the stationery at a time as in the case of a rotary platen having disappearing pins, transverse alignment of the holes of the two series insures simultaneous full engagement of a hole in both series with pins of the feeding device, whereby positive alignment is insured.

Engagement of the two series of apertures with a pair of corresponding pin feed devices on a writing machine maintains the superposed strips accurately aligned with the writing line of the machine and serves to hold the superposed form lengths in mutual registration. The same pin feed device may be used with strips of varying width without any adjustment or alteration and the margin of the strips opposite the apertured margin is available for inscription.

To prevent relative shifting of the superposed form lengths, the manifolding strips, according to the present invention, are bound together along the margin 28, for example, by means of staples 21 at longitudinally spaced intervals.

Preferably, at least one staple is provided in each form length. A weakening line of perforations 23 is provided in each of the superposed strips between the parallel series of apertures 30 and 31.

After inscription of each form length, the marginal portion, bearing staples 21, is severed from the body of strips to permit separation of the superposed copies. By forming the said severing line between the two series of apertures 30 and 31, apertures 30 are removed from the inscribed portion of the form length when the marginal portion thereof is severed. If it is desired to replace one or more copies of the form length in the writing machine for inscription of additional data thereon, the remaining series of apertures 31 may be reengaged with the corresponding pin feed device, whereby the delineations and written matter are accurately realigned in their original relation with the writing line of the machine.

As disclosed in United States Patent No. 2,083,295 issued June 8, 1937 to Conklin, the present transfer strips 22 in the manifolding stationery of Fig. 1 are provided with transverse weakening lines 25 which are in registration with the sev-

ering lines 24 of the record strips for the major portion of their length, but preferably offset from the severing lines 24 adjacent the center of the strips. As a result, upon severing the written form lengths from the superposed manifolding strips, each of the transfer sheets is left with a tab 27 protruding beyond the transverse severed edge of the record strips 20, while at the same time, a notch is formed in the bottom of each adjacent carbon sheet.

After removal of the stapled portion at the margin 28, the tabs 27 may be grasped with the thumb and forefinger of one hand, while the record sheets are held between the thumb and forefinger at the opposite margin over the notches in the carbon sheets, and the latter may be pulled out as a whole from between the form length record copies.

Moreover, to aid in maintaining the superposed record and transfer sheets of each form length in mutual registration, the superposed strips are preferably secured together by means of staples 29, preferably at the center of the tabs 27 in the carbon sheets, and coincident with the transverse weakening lines 24 of the record strips. Upon severing the superposed strips transversely along the weakened lines 24 and 25, the staple 29 is released from the record strips 20 but still holds the tabs 27 of the transfer strips together, facilitating removal of all of the transfer strips at the same time.

The transfer strips 22 may extend laterally to the outer margin of the record strips, if desired, so that they are retained in place by the marginal staples 21.

The feeding and margin severing device, according to the present invention, with which manifolding stationery of Fig. 1 is adapted to be used, is illustrated in Figs. 2 to 8 inclusive, and is shown mounted on the left-hand end of a conventional typewriter platen. The latter comprises a shaft 32 journaled in a stationary bearing plate 34, and carrying a terminal knob 33 for manual rotation thereof, and a platen roll 35 secured thereto by a set screw 36.

The end of the platen roll 35 is reduced to receive a pin ring 37, the outer surface of which is preferably cylindrical and of the same diameter as the platen roll 35. Adjacent its inner end, ring 37 carries a circumferential annular series of radially projecting feed pins 38.

In order to secure the ring 37 to the platen, one or more lugs 39 may be provided thereon which project inwardly from the ring to engage a corresponding socket 40 in the platen. As shown in Fig. 3, the said projections may be formed integral with one or more of the pins 38.

Adjacent its outer end, the ring 37 is provided with an annular series of axially elongated slots 41 which are preferably axially aligned, as illustrated, with the pins 38. The reduced portion of the platen roll 35 is provided with a series of grooves 42 extending axially inward from the end of the roll beneath each of the slots 41.

Each of the grooves 42 is adapted to receive a slide plate 43 carrying a pin 44 which extends through the slot 41 in ring 37. The slide plates 43 are adapted to slide to and fro in axial direction in grooves 42 to move pins 44 back and forth in the slots 41.

The inner ends of the slots 41 are so spaced from pins 38 that when pins 44 are disposed at the inner ends of said slots, the two sets of pins 44 and 38 are adapted to register respectively

with apertures 39 and 31 in the manifolding stationery of Fig. 1.

Means is provided, according to the present invention, to control movement of the pins 44 in the slots 41 at predetermined points in their travel incident to the rotation of the platen 35. This means comprises a stationary cam plate 45 secured to the bearing plate 34 adjacent the end of the platen roll, said cam plate having a peripheral cam groove 46 for engaging tabs 47 on the outer ends of the slide plates 43.

The manifolding strip is fed to the platen from the rear, passing around the platen from the bottom to the top. At the point where apertures 31 of the stationery first engage pins 38, the cam groove 46 is parallel to a plane perpendicular to the axis of the platen and consequently to the annular series of pins 38, and holds pins 44 inward so that they register with apertures 30 in the separable bound margin strip of the stationery. The engagement of the two sets of pins with the parallel series of apertures insures positive advancement of the strips, and holds the superposed record strips and transfer strips in accurate alignment at the writing line of the machine.

As indicated in Fig. 2, cam groove 46 continues parallel to the annular series of pins 38 so as to hold the pins 44 inward at the inner end of slots 41, substantially until the said pins attain the writing line 48 at the front of the platen. At this point, or just beyond, cam groove 46 diverges from the end of the platen. Consequently, as the stationery travels beyond this point, pins 44 move outwardly from pins 38, applying sufficient tension to the strips at the severing line 23 to tear off the bound margin strip containing apertures 30 and staples 21.

The severed margin strips, as well as the record strips leave the feed pins at the top of the platen in the usual manner, any conventional guide or stripper means, such as member 50 being used for this purpose. Beyond this point, cam groove 46 converges inward toward the platen resuming its initial position, parallel to the annular series of pins 38 in advance of the point where the pins first engage the incoming strips of stationery. As a result, pins 44 are progressively returned to their inward positions in slots 41, whereby they are again adapted with pins 38 to engage the apertures 30 and 31 in the incoming stationery on the receiving side of the platen. During the severing operation, pins 38 retain the inscribed portion of the strips in accurate alignment by continued engagement with the perforations 31 until the strips leave the platen on its delivery side.

As the inscribed forms issue from the machine, they may be severed at will along transverse severing lines 24 and 25. The transfer sheets 22 are removed as a unit from the record sheets 20 by grasping the tabs 27 at one end of the form length and the record sheets at the corresponding notch at the opposite margin, and pulling the two apart. The transfer sheets, which are held together by the central staples 29, are snapped out as a unit, leaving the inscribed forms ready for distribution.

As stated above, certain of the inscribed record sheets may be reinserted into the machine in such a manner that apertures 31 reengage pins 38. Additional data may then be inscribed on the forms, the said pins insuring proper realignment of the printed forms with the writing line of the machine.

By virtue of the fact that both sets of pins are

disposed at the same end of the platen, the stationery may be made of any desired width which can be accommodated by the length of the platen without any change in the feeding and severing mechanism.

A conventional type of manifolding stationery is shown in Fig. 9, differing from the stationery of Fig. 1, in that the longitudinal series of pin feed apertures 31a in the body of the strips is formed at the margin opposite the bound margin 28a, instead of adjacent the longitudinal severing line 23a as in the case of apertures 31. Otherwise, the stationery of Fig. 9 is similar to that of Fig. 1, comprising superposed record strips 20a, interleaved transfer strips 22a, transverse severing lines 24a and 25a at form length intervals, a weakened longitudinal severing line 23a adjacent margin 28a, a series of pin feed apertures 30a and staples 21a in the severable marginal portion of the strips, and staples 29a disposed along the transverse severing lines at the midportion of the strips. The stationery of Fig. 9 is adapted to be used with a modification of the feeding and severing device of the present invention, illustrated in Fig. 10.

In the modified feeding and severing device shown in Fig. 10, a ring is provided on the end of the platen, similar to ring 31, except that pins 38 are omitted. The pins 44a carried by slide plates 43a protrude through slots similar to slots 41 in the said ring, and the slide plates 43a are axially movable in grooves in the reduced end of a platen beneath each of the said slots in the same manner as slide plates 43. The tabs 47a on the said slide plates engage the groove 46a on the fixed cam member 45a which is of the same construction as cam member 45. A stripper 50a is shown for stripping the severed margin 28a from pins 44a.

On the lower side of the platen, from the point at which the stationery first engages the feed pins substantially to the writing line, indicated by the position of the type bar 49, the groove 46a, like groove 46, is parallel to a plane perpendicular to the axis of the platen. From this point onward, the groove diverges progressively from the end of the platen for a short distance. Beyond the point where the stationery is stripped from the feed pins, the groove converges again to its inner position, becoming again parallel with a plane perpendicular to the platen axis, at the rear of the platen in advance of the point where the incoming stationery engages pins 44a.

Adjacent the opposite end of the platen, an annular series of fixed pins 38a are provided which are adapted to enter apertures 31a at the right-hand margin of the stationery illustrated in Fig. 9, when pins 44a enter perforations 30a in the separable margin 28a of the stationery at the left.

As the stationery is fed beyond the writing line, pins 38a retain the inscribed portion of the strips in registration and alignment, while pins 44a move divergently outward relative to pins 38a, applying transverse severing tension at the weakened severing line 23a, and severing the bound marginal portion of the strip, containing apertures 30a, from the inscribed portion of the strip.

If desired, inscribed copies of any form length may be reinserted into the machine after severing them from the strip, and reregistered relative to the writing line of the machine by reengaging apertures 31a with pins 38a. However, the spacing of pins 38a from pins 44a determines the width of the stationery which can be fed and

severed, and if it is desired to use stationery of different widths, the axial position of at least one set of pins must be altered, or else the platen must be replaced by one having sets of pins of suitable spacing. For this reason, the arrangement illustrated in Figs. 1 to 8 is preferred.

The stationery per se illustrated and described herein forms the subject matter of my application Serial No. 420,783, filed November 28, 1941, which is a division of this application.

Variations and modifications may be made within the scope of this invention and portions of the improvements may be used without others.

I claim:

1. In a strip feeding and severing device, means for advancing a strip having a longitudinal weakened severing line past a severing position; means retaining the portion of the strip on one side of the severing line against lateral movement toward said line at the severing position; strip-engaging means engaging the other portion of the strip in advance of said severing position, and maintaining said engagement as the strip passes beyond said position; and automatic means for progressively moving said strip-engaging means divergently outward from the severing line incident to operation of the strip-advancing means as the strip moves beyond said severing position, whereby the strip is subjected to transverse tension sufficient to sever it progressively along the severing line at the severing position.

2. In a strip feeding and severing device, a pair of positive strip-engaging means for advancing a strip having a longitudinal weakened line past a severing position, said strip-advancing means respectively engaging the strip on opposite sides of said severing line for advancement thereof as it passes through and beyond the severing position; and means for moving at least one of said strip-engaging means laterally and divergently from the direction of strip feed beginning at the severing position, incident to strip-advancing operation thereof, the other strip-engaging means meanwhile retaining the strip against lateral movement, whereby sufficient lateral tension is applied to the strip to sever it progressively along said severing line at the severing position.

3. In a strip feeding and severing device, positive means for engaging a strip of material having a longitudinal weakened severing line on one side of the severing line and retaining the engaged position of the strip against lateral displacement, a traveling series of feed pins engaging a longitudinal series of apertures on the other side of said weakened severing line, said feed pins and said strip-engaging means engaging said strip as it passes through a severing position; and means for progressively moving said pins and strip engaging means in divergent paths as they pass beyond the severing position while in engagement with the strip and incident to forward operation of the pins, to apply lateral tension to the strip to sever it progressively at the severing position.

4. In a strip feeding and severing device, a rotary platen over which a continuous strip of stationery having a longitudinal weakened severing line is advanced; a pinwheel rotated with said platen and engaging a longitudinal series of apertures in the strip on one side of said severing line during passage of the strip past a fixed severing position; a series of pins rotating with said platen and engaging a longitudinal series of apertures in said strip on the opposite side of said severing

line; means for retaining the latter series of pins against lateral displacement from the point where they engage the strip to said severing position, and for progressively moving said pins laterally outward from the pinwheel as they pass beyond the severing position in engagement with the strip, whereby sufficient tension is applied to the strip to sever it along said severing line at the severing position; and means for returning said pins to their original inward position after the strip is severed and before they reengage the strip on the receiving side of the platen.

5. In a strip feeding and severing device, means for advancing a strip having a longitudinal weakened severing line adjacent one margin thereof past a severing position; means engaging the body portion of the strip adjacent said severing line, and retaining the engaged portion of the strip against lateral movement toward the line at the severing position; strip-engaging means engaging the severable margin of the strip in advance of said severing position and maintaining its engagement therewith as the strip passes beyond said position; automatic means actuated by operation of said strip advancing means, for moving said strip-margin engaging means outward from the severing line as it passes beyond the severing position, whereby sufficient transverse tension is applied to the strip to sever the margin therefrom along the severing line at the severing position.

6. In a strip feeding and severing device, a rotary platen over which a continuous strip of stationery having a longitudinal weakened severing line adjacent one margin, is advanced; a pinwheel rotated with said platen and engaging a longitudinal series of apertures in the body portion of the strip adjacent said severing line during passage of the strip past the fixed severing position; a series of pins adjacent the pinwheel, rotated with said platen, and engaging a longitudinal series of apertures in the severable margin of said strip; means for retaining the latter series of pins against lateral displacement from the point where they engage the strip to said severing position, and for progressively moving said pins divergently outward from the pinwheel as they pass beyond the severing position in engagement with the strip, whereby sufficient lateral tension is applied to the strip to sever the margin thereof along said severing line; and means for returning said pins to their original inward position after the margin of the strip is severed and before they reengage the strip on the receiving side of the platen.

7. In a strip feeding and severing device for advancing a strip having a longitudinal severing line adjacent the margin thereof, a pinwheel mounted on the platen for rotation therewith and engaging a longitudinal series of apertures in the main portion of the strip adjacent said severing line; a collar secured to the adjacent end of the platen having an annular series of axially elongate slots therein; a plurality of slide members carried in axial grooves in the end of the platen beneath said slots in the collar; a pin on each of said slide members projecting through the corresponding slot of the collar, and slidable in the slot; a fixed cam member adjacent the end of the platen; and means on said slide members engaging said cam member for retaining the slide members and the pins carried thereby in an inward position from a point where the pins engage the incoming strip to a severing position, thereafter moving them positively and progres-

sively outward as they pass beyond the severing position, whereby sufficient lateral tension is applied to the strip to sever the margin of the strip along said severing line; and means for moving the slide members and pins back to their original inward position before the strip is reengaged by the pins on the receiving side of the platen.

8. In a strip feeding and severing device for advancing a strip having a longitudinal severing line adjacent a margin thereof, a pinwheel mounted on the platen for rotation therewith and engaging a longitudinal series of apertures in the main portion of the strip adjacent said severing line; a collar secured to the adjacent end of the platen having an annular series of axially elongate slots therein; a plurality of slide members carried in axial grooves in the end of the platen beneath said slots in the collar; a pin on each of said slide members projecting through the corresponding slot of the collar and slidable therein together with the slide member; a fixed cam member adjacent the end of the platen; and means on said slide members engaging said cam member for retaining the slide members and pins carried thereby in an inward position from a point where the latter engage the incoming strip to a severing position, thereafter moving them positively and progressively outward as they pass beyond the severing position, whereby sufficient lateral tension is applied to the strip to sever the margin thereof along said severing line, said cam thereafter moving the slide members back to their original inward position before the strip is reengaged by the pins carried thereby on the receiving side of the platen.

9. In a strip feeding and margin severing device, a pair of laterally spaced positive strip-engaging means movable in unison in the direction of strip advancement for progressively engaging a strip of stationery adjacent one of its margins during advancement thereof; and means for progressively moving one of said strip-engaging means divergently from the other incidental to strip advancing operation and during engagement of the strip by said means.

10. In a strip feeding and margin severing device, a pair of laterally spaced positive strip-engaging means movable in unison in the direction of strip advancement for progressively engaging a strip of stationery adjacent one of its margins during advancement thereof; and means for progressively moving that one of said means which is closest to the margin of said strip, divergently from the other, incidental to strip advancement and during engagement of the strip by said means.

11. In a strip feeding device, multiple means for progressively engaging a strip of stationery for advancement thereof adjacent one of its margins, said multiple means being laterally spaced one from the other, for engaging said strip at longitudinally spaced intervals, and movable in unison in parallel paths in the direction of strip advancement, the successive portions of said strip engaged by said respective means being aligned transversely of the strip.

12. In a strip feeding device for advancing an apertured continuous strip of stationery, a plurality of laterally spaced series of pins movable in parallel paths in direction of strip advancement for progressively engaging correspondingly laterally spaced series of apertures adjacent one margin of the strip during advancement thereof, the pins of the respective series being in mutual

alignment transversely of the direction of strip feed.

13. In a strip feeding device for advancing an apertured continuous strip of stationery, a plurality of coaxially arranged, laterally spaced, rotatable series of pins for progressively engaging correspondingly laterally spaced series of apertures adjacent one margin of the strip of stationery during advancement thereof, the pins of the respective series being in alignment transversely of the direction of strip feed.

14. In a strip feeding device having a rotatable platen over which continuous apertured strips of stationery are advanced, a pair of axially spaced series of pins at one end of the platen, rotatable therewith in parallel paths for progressively engaging correspondingly laterally spaced series of apertures in the strips during advancement thereof, pins of the respective series being mutually aligned transversely of the direction of strip feed.

15. In a strip feeding and severing device, a pin-bearing body rotatable on an axis; a series of radially extending pins carried thereby for movement axially of the body; means for moving the pins axially of the body, said pins engaging apertures in a portion of the strip severable therefrom and severing the same as a result of said axial movement of the pins while engaging said portion; and means acting upon the remaining portion of the strip for holding it against movement during the severing operation.

16. In a strip feeding and severing device, a pin-bearing body rotatable on an axis; a series of radial strip-engaging pins carried thereby for movement axially of the body; means for moving said pins axially of the body seriatim in response to rotation of said body, said pins engaging apertures in a portion of the strip severable therefrom and severing the same as a result of said axial movement of the pins incident to the feeding of the strip; and means acting upon the remaining portion of the strip for holding it against lateral movement during the feeding thereof whereby the severable portion is removed therefrom.
17. In a device for feeding apertured continuous strips, a pin-bearing body having pins projecting therefrom and engaging said apertures in a severable portion of said strip; means for moving said pins seriatim laterally of said strips incidental to the strip-feeding operation of said device for moving said portion therewith; and means acting on the remaining portion of the strip for holding it against lateral movement whereby the severable portion is severed incident to the strip-feeding operation.
18. A pinwheel having a circumferential series of radially extending pins mounted thereon for bodily movement transverse to the plane of rotation thereof and having another circumferential series of radially extending pins fixed against such bodily movement.

ARTHUR A. JOHNSON.
